Design No. 537.

Hager, Richmond & Smith
Hearth Plate Design

Patented Dec. 21, 1852.

Des. 537

James Wager, Volney Richmond & Harvey Wager of Troy, N.Y.
Letters Patent No. 537. - Dated Dec. 21. 1852.

The schedule referred to in these Letters Patent, and making part of the same.

Des. 537

To all whom it may concern:

Be it known that we James Wager, Volney Richmond and Harvey Smith of the City of Troy and County of Rensselaer in the State of N. Y. have invented or produced a new design to be cast upon the plates of a hearth for a cooking stove, & we do hereby declare that the following is a full and exact description of the same. The drawing Fig. A. represents this hearth in form and shape with the sunk ash pit, the bottom of which being an inclined projection towards the front on which the ashes are deposited and slide forward. The outer edge of this hearth is ornamented with a bead, a cove and a bead and fillet moulding. The heavy cove moulding between the two bead mouldings is ornamented with oblong drop ornaments regularly placed quite around it.

Having thus fully described our design what we claim as new and for which we desire to secure Letters Patent is the foregoing Design and configuration of the plates, forming an ornamental design for a stove as illustrated and represented by the Drawings.
